HYDRAULIC PUMP

Elysée Eynard, Lyon, France

Application December 29, 1945, Serial No. 637,935
In France March 25, 1944Section 1, Public Law 690, August 8, 1946
Patent expires March 25, 1964

9 Claims. (Cl. 103—161)

1

My invention refers to hydraulic pumps such as those intended to be used in connection with hydraulic rams or presses and like apparatus requiring a widely variable pressure increasing up to very high values.

In pumps of this kind if the pistons are so dimensioned as to provide easily high pressures, the output is necessarily reduced and the approach of the piston of the press is extremely slow. If on the contrary the pump is arranged to provide a rapid movement of the press, the maximum pressure remains limited on the one hand because the torque becomes rapidly too high for a motor of average power, and on the other hand because the mechanical strength of the pump parts becomes insufficient.

A first object of my invention is to provide a pump which will permit of obtaining automatically an output and a pressure varying inversely of each other within extremely wide limits.

Another object of my invention is to provide a pump which will automatically require a substantially constant driving torque irrespective of output and pressure variations.

A further object of my invention is a pump of the aforesaid character, comprising a plurality of sets of pistons and cylinders of different cross-sections, and pressure-actuated means adapted to eliminate the sets of larger cross-section as the pressure rises. This elimination is preferably effected by means of a by-pass while a non-return valve is provided to prevent liquid from flowing back from the high-pressure side of the pump.

Still a further object of my invention is a pump of the aforesaid character, wherein the cylinders are radially disposed on the same rotating member, the pistons being connected to a second rotating member eccentrically disposed with respect to the former, and means being provided to reduce this eccentricity when the delivery pressure rises.

My improved pump also comprises a casing forming a tank for the liquid to be pumped and comprising a distributor to control the hydraulic press associated with the pump.

In the annexed drawings:

Fig. 1 is a general longitudinal section of a pump established in accordance with my invention.

Fig. 2 is a transverse section thereof taken along line II—II of Fig. 1. In this Fig. 2 the plane of section of Fig. 1 is indicated by line I—I.

Fig. 3 is a partial transverse section taken along line III—III of Fig. 1.

Fig. 4 is another partial transverse section taken along line IV—IV of Fig. 1.

Fig. 5 is a fragmental section taken along line V—V of Fig. 2.

The pump illustrated comprises a general cas-

2

ing 1 (Figs. 1 and 2) traversed by a fixed shaft 2 rotatably supporting a rotor 3 in which there are formed two rows of radial cylinders, viz. respectively cylinders 4 of large diameter (Figs. 1 and 2) and cylinders 5 of smaller diameter (Figs. 1 and 3). Pistons 6 and 7 are slidable in cylinders 4 and 5 respectively and they are pivotally connected with shoes 8 and 9 adapted to slide in circular grooves 10 and 11 formed on the internal periphery of a drum member 12 enclosing rotor 3.

Drum 12 is not co-axial to shaft 2. It is rotatably supported by bearings carried by side members 14 adapted to slide vertically against a slide 15 within casing 1 (Fig. 2). The two side members 14 are moreover connected by longitudinal stays 16 (Figs. 1 and 2) fixed to vertical columns 17 which pass through the upper part of casing 1 to carry a common connecting cross-member 18. The latter slides on vertical guide rods 19 provided with strong compression springs 20 tending to push member 18 downwardly.

It will be understood that the above-described arrangement permits drum 12 to be displaced upwards against the action of springs 20 between a lower position corresponding to maximum eccentricity (position illustrated in the drawings) and an upper position corresponding to substantially zero eccentricity.

Cross-member 18 is also submitted to the action of a hydraulic device comprising a piston 21 (Figs. 1 and 2) slidable within a small vertical cylinder 22 provided above casing 1, the said piston tending to push the said member upwardly. Piston 21 is made in two parts with a mass of packing material between them. The upper part abuts against member 18 while the lower part is fixed on a rod which passes through the upper part and through member 18, and carries a compression spring 24 tending to push rod 23 upwardly to ensure perfect tightness of the packing.

Shaft 2 is formed as a distributor for the two sets of cylinders 4 and 5. It comprises a first hollow portion 25 connected to an inlet pipe 26. The latter is itself connected to the base of casing 1 by piping not shown. In the plane of cylinders 4, shaft 2 is so cut as to leave two crescent-shaped recesses 27 and 28 (Fig. 2) adapted to respectively form an inlet and an outlet collector, the former being connected to the hollow part 25 through a longitudinal bore 29, while the other communicates with a longitudinal bore 30 forming a delivery channel towards the end of shaft 2 opposed to pipe 26 (Fig. 1). Shaft 2 is similarly arranged in the plane of cylinders 5 to form two recesses 31 and 32 (Fig. 3). The former communicates with the above-described bore 29 which extends sufficiently through the length of the shaft, while the second communicates with a special delivery bore or channel 33 (Figs. 1 and

3) extending towards the right end of shaft 2.

There is provided in the rear wall of casing 1 a vertical bore 34 adapted to form a high-pressure chamber. Bore 34 communicates with channel 33 through a non-return ball valve 35. And channel 30 in turn communicates with channel 33 through another non-return ball valve 36 (Figs. 1 and 4).

Channels 30 and 33 open at the right hand end of shaft 2 (Fig. 1) and they accommodate two pistons, 37 and 38 respectively, which bear against a common movable abutment 39 pressed towards the left by a strong spring 40 bearing against a cap 41 fixed to casing 1 and fitting over the end of shaft 2.

Shaft 2 is formed with a transverse port 42 (Fig. 1) providing a communication between channel 30 and the interior of casing 1. Port 42 is normally closed by piston 37.

The rear wall of casing 1 also encloses a distributor comprising a horizontal transverse bore 43 (Figs. 1 and 4) which houses a double slidable piston-valve 44 with an actuating rod 45 passing through a stuffing box 46, the opposite end of the bore being closed by a cover 47. Bore 43 crosses the above-described vertical bore 34 and it is connected with two tubes 48 and 49 forming the delivery (or return) of liquid under pressure. These two tubes are connected with the two chambers of the cylinder of the hydraulic press or ram actuated by the pump. The two ends of bore 43 are connected with the inside of casing 1 through two small spring-loaded valves, each comprising (Fig. 5) a longitudinal bore 50 enclosing a piston 51 pressed by a spring 52 against a shoulder forming a seat, spring 52 resting against a plug 53. A port 54, normally covered by piston 51, provides a communication between bore 50 and the interior of casing 1.

The operation is as follows:

Rotor 3 is driven through a pair of reducing gears 55 and 56, the former being, for instance, keyed on the shaft of an electric driving motor. Drum 12 being initially at its maximum eccentricity under the action of springs 20, the cylinders 4 and 5 deliver a large output of liquid under low pressure into the high-pressure chamber 34 through channels 30 and 33. Pistons 37 and 38 are at their left-hand position of Fig. 1 and port 42 is covered.

As the pressure rises, the reaction exerted by drum 12 against side member 14 causes the latter to rise against the action of springs 20 and the stroke of pistons 6 and 7 thus decreases, which tends to maintain the driving torque substantially constant in spite of pressure increase.

When the pressure reaches a sufficient value, pistons 37 and 38 are displaced towards the right against the action of spring 40, whereby port 42 is progressively uncovered, which suppresses the action of cylinders 4, the delivery of which freely returns to casing 1. Ball 36 prevents liquid from flowing back from channel 33, so that the pressure goes on rising under the sole action of the small-section cylinders 5. The reaction against side members 14 being thus diminished, the eccentricity of drum 12 returns to a maximum or at least to a relatively high value.

It will be remarked that the pressure rapidly reaches such a value that piston 38, acting alone, maintains spring 40 in the compressed state. Piston 37 is thus free and the by-pass through port 42 is effected without any counterpressure. For instance if spring 40 is so set that port 42 begins to be uncovered at a pressure p under the

action of pistons 37 and 38, ball 36 closes as soon as this pressure is attained and the delivery of cylinders 4 through port 42 takes place under a counter-pressure p . But the pressure acting on piston 38 rises and this counterpressure decreases, the sum of the forces applied by the two pistons on abutment 39 remaining substantially constant. When the delivery pressure of cylinders 5 reaches a valve P , cylinders 4 thus operate without any counterpressure.

As the pressure continues to rise, side members 14 again rise under the reaction of pistons 7 against drum 12. But, owing to the small cross-section of cylinders 5, this reaction is reduced and it would be insufficient to maintain the driving torque substantially constant. It is therefore assisted by the hydraulic device 21-22 which is connected to the high-pressure chamber 34 through an external piping diagrammatically indicated at 57 in Fig. 1.

The liquid under high pressure within chamber 34 flows towards the hydraulic press or the like through one of pipes 48, 49 (Fig. 4) according to the position of the double piston valve 44 (in Fig. 4, the outlet takes place through pipe 48), while the other pipe (pipe 49 in Fig. 4) is connected with casing 1 through the corresponding spring-loaded valve 51-52 which ensures a sufficient counterpressure to prevent air admission into the liquid circuit.

I claim:

1. In a hydraulic pump, a casing, a shaft having its opposite ends fixedly supported in said casing, a rotor rotatably supported on the shaft, drive means for rotating said rotor, two series of cylinders in said rotor disposed radially of said shaft, the cylinders of one series being of a different diameter than the cylinders of the other series and being spaced therefrom axially of the shaft, pistons operatively disposed in said cylinders, a drum surrounding said rotor, connecting means movably securing the outer ends of the pistons to said drum, yieldable means initially retaining the drum in eccentric relation to the axes of the shaft and rotor, fluid distributing means in said shaft including inlet and outlet ports to said cylinders, a fluid supply connection at one end of said shaft in communication with said inlet ports, and a fluid high pressure chamber in said casing having one-way valve controlled communication with said outlet ports, whereby upon rotation of said rotor, said pistons are reciprocated and act to pump fluid through said fluid supply connection into said pressure chamber; said fluid distributing means including a pair of elongated bores communicating at corresponding ends thereof with the outlet parts of the respective series of cylinders, said bores having said one-way valve controlled communication with said high pressure chamber, a by-pass fluid port in one of said bores, a spring backed piston in said one bore normally closing said by-pass port, whereby upon increased pressure within said one bore, the piston is moved against the action of said spring to open the by-pass port and thus render the associated series of cylinders inoperative to pump fluid into said high pressure chamber.

2. In a hydraulic pump, a casing, a shaft having its opposite ends fixedly supported in said casing, a rotor rotatably supported on the shaft, drive means for rotating said rotor, two series of cylinders in said rotor disposed radially of said shaft, the cylinders of one series being of a different diameter than the cylinders of the

other series and being spaced therefrom axially of the shaft, pistons operatively disposed in said cylinders, a drum surrounding said rotor, connecting means movably securing the outer ends of the pistons to said drum, yieldable means initially retaining the drum in eccentric relation to the axes of the shaft and rotor, fluid distributing means in said shaft including inlet and outlet ports to said cylinders, a fluid supply connection at one end of said shaft in communication with said inlet ports, and a fluid high pressure chamber in said casing having one-way valve controlled communication with said outlet ports, whereby upon rotation of said rotor, said pistons are reciprocated and act to pump fluid through said fluid supply connection into said pressure chamber; said drum being rotatably supported within a pressure member supported within the casing by guide means for vertical movement thereof in accordance with changes in the eccentricity of the drum as occasioned by reaction of the pistons against fluid under pressure.

3. In a hydraulic pump, a casing, a shaft having its opposite ends fixedly supported in said casing, a rotor rotatably supported on the shaft, drive means for rotating said rotor, two series of cylinders in said rotor disposed radially of said shaft, the cylinders of one series being of a different diameter than the cylinders of the other series and being spaced therefrom axially of the shaft, pistons operatively disposed in said cylinders, a drum surrounding said rotor, connecting means movably securing the outer ends of the pistons to said drum, yieldable means initially retaining the drum in eccentric relation to the axes of the shaft and rotor, fluid distributing means in said shaft including inlet and outlet ports to said cylinders, a fluid supply connection at one end of said shaft in communication with said inlet ports, and a fluid high pressure chamber in said casing having one-way valve controlled communication with said outlet ports, whereby upon rotation of said rotor, said pistons are reciprocated and act to pump fluid through said fluid supply connection into said pressure chamber; a bore in said casing intersecting and communicating with said high pressure chamber, fluid outlets from said bore to the exterior of the casing, fluid outlets from said bore to the interior of the casing, and double piston valve means in said bore operative to alternately connect said first outlets in opposite respective relation to said chamber and to said second outlets.

4. In a structure of the character disclosed, a casing, a shaft having its opposite ends non-rotatably supported in opposite walls of the casing, a rotor rotatably supported on the shaft, drive means for rotating the rotor, side members disposed within the casing and connected therewith for vertical sliding movement, a drum surrounding the rotor and rotatably supported within the side members, two series of cylinders in the rotor in radial relation to the shaft, the cylinders of one series being of substantially greater diameter than the cylinders of the other series and spaced therefrom axially of the shaft, spring means reacting against said side members for initially retaining the drum in eccentric relation to the axes of the shaft and rotor, pistons operatively disposed in the cylinders and having their outer ends pivotally and circumferentially slidably connected with the drum, fluid distributing

means in the shaft including inlet and outlet ports to the cylinders, a fluid supply connection from the casing to said inlet ports, a vertically disposed fluid pressure chamber in said casing,

5 said outlet ports of the cylinders of the respective series thereof communicating with an elongated bore included in said distributing means, and one-way valve controlled ports between said bores and said pressure chamber adjacent the other end of the shaft.

10 5. The structure according to claim 4, together with a spring backed piston in each of said bores beyond said one-way valves, a port providing communication between one of said bores and said casing, the associated piston normally closing said port and being movable under increase of fluid pressure by said pump to open said port.

15 6. The structure according to claim 4, wherein said side members are interconnected by a cross member above the casing, a piston operatively disposed in a cylinder in the casing and having its upper end engaged with said cross member, and a fluid connection between said pressure chamber and said cylinder.

20 7. The structure according to claim 4, wherein said side members are interconnected by longitudinal stays, vertical columns extending upwardly from said stays through openings in said casing for providing said vertical sliding movement, a cross-member interconnecting the upper ends of the columns, a pair of rods extending upwardly from said casing and through openings in said cross-member, and said spring means surrounding said rods and engaging said cross-member.

25 8. The structure according to claim 4, together with a horizontal bore in said casing intersecting and communicating with said pressure chamber fluid outlets from said bore at each side of said pressure chamber leading to said casing and exterior thereof, and a double piston valve slidably disposed in said bore for controlling said outlets.

30 9. In a hydraulic pump, a plurality of sets of rotary pump cylinders and pistons, the cylinders 45 of each set having a different diameter with respect to those of the other sets respectively, fluid distributing means for each set comprising inlet and outlet ports, a common high-pressure chamber; one-way valve means connecting the outlet 50 port of each set to said high-pressure chamber; means for by-passing the inlet and outlet ports of each set of cylinders of larger diameter; and pressure-responsive means for actuating said by-passing means to render said sets inactive in succession commencing with those of largest diameter.
